William W. Bates

United States Patent Office.

WILLIAM W. BATES, OF CHICAGO, ILLINOIS.

Letters Patent No. 64,739, dated May 14, 1867.

IMPROVED METHOD OF HANGING CENTRE-BOARDS OF VESSELS.

The Schedule referred to in these Letters Patent and making part of the same.

TO ALL WHOM IT MAY CONCERN:

Be it known that I, WILLIAM W. BATES, of the city of Chicago, in the county of Cook, and State of Illinois, have invented new and useful improvements in "the Method of Hanging Centre-Boards in Vessels;" and I do hereby declare that the following is a full and exact description thereof, reference being had to the accompanying drawings, making part of this specification, in which—

Figure 1 represents the elevation of the centre-board and the frame to hang it.

Figure 2 represents cross-section of the same along the line M N.

Figure 3 represents the ends of the frame-arms when one bolt is used for suspension of the frame.

Figure 4 is the plan of an eye-bolt; and

Figure 5, the section of the end of the board when frame-plates are welded together.

Similar letters of reference in each of the several figures indicate corresponding parts of the arrangement.

The nature of my invention consists in pinning the centre-board to a metallic frame instead of to the sides of the centre-board case or box, as the case is now, and to hang said frame on to the head ledge of and within the said case or box, in the manner as will be hereinafter fully explained.

To enable others skilled in the art to make and use my invention I will proceed to describe its construction and operation.

The fore part of the centre-board A is cut away on both sides for the thickness of plates of the sustaining or hanging frame B, which consists of a pair of angular plates, b b, whose fore ends are welded to heavy, square cross-pieces C C, or simply welded together, as on fig. 5, the edge of the centre-board being shaped accordingly. At their angle these plates are bent inside, so as to be overlapped by the pintle-plates D D, and have eyes, into which enter the pintles d d, set on the inner sides of the pintle-plates, which last, in their turn, are firmly secured by bolts to the centre-board, the outside surfaces of the plates of the frame B and of pintle-plates D D being made flush with the surface of the centre-board. There are eye-bolts or eye-straps E E secured to the head ledge F of the centre-board box G, for the purpose of hanging the frame B, the opening of said eyes being made oval in the athwart-ship direction, as shown in fig. 4, to allow the centre-board to have some lateral motion. There may be two different ways of suspending frame B to the head-ledge eye-bolts E E. One is to have the cross-pieces C C, or the welded fore ends of plates b b, provided with pintles f f, by means of which frame B may be suspended on the eye-bolts E E, as shown on fig. 1; and in this case a block, H, has to be secured inside of the box G to prevent frame B from being raised out of the eye-bolts E E. The other is to have the cross-pieces C C, or the welded ends of the plates b b, provided with eyes instead of pintles, and the frame B suspended by means of a long bolt, I, passing through the eyes and the eye-bolts, as shown on fig. 3. In case an iron centre-board is desirable I propose to make it out of thin iron plates, in the shape of a box, with a space inside, placing my pintle-plates and the sustaining frame either inside or outside of the centre-board.

The advantages of my system of hanging the centre-boards in vessels are the following: The pin on which the centre-boards revolve now is placed below the water line, passing through the entire box, and therefore produces leakage and damages cargoes, while my pintle-plates, being placed inside of the box, produce no leakage at all. With the present system, to unship the centre-board for repairs it is necessary to first unload the cargo in order to reach the pin, while with my arrangements the board may be taken out of its box for repairs and reshipped again any time without touching the cargo, a fact to be appreciated particularly by ship-owners and masters.

What I claim as my invention, and desire to secure by Letters Patent, is—

I claim suspending the centre-board of vessels by means of the frame B, in combination with the plates D, constructed and arranged substantially as described.

WILLIAM W. BATES.
